UNITED STATES PATENT OFFICE.

GABRIEL FELSENTHAL, OF CHICAGO, ILLINOIS.

POWDER-RECEPTACLE.

1,347,149.

Specification of Letters Patent.

Patented July 20, 1920.

Application filed December 20, 1919. Serial No. 346,345.

To all whom it may concern:

Be it known that I, GABRIEL FELSENTHAL, a citizen of the United States, and resident of the city of Chicago, in the county of Cook and State of Illinois, have invented certain new and useful Improvements in Powder-Receptacles, of which the following is a specification.

My present invention relates more particularly to what are commonly called vanity cases and aims to provide a simple and economical construction in which the powder receptacle or compartment may be made and assembled as a unitary article and thereafter incorporated in the box or case proper.

The invention includes the novel feature of construction and arrangement and combination of parts hereinafter described and defined in the appended claim.

An embodiment of my invention is illustrated in the accompanying drawings in which,

Figure 1 is a transverse sectional view through the complete case and

Figs. 2 to 5 are detail views.

Referring by reference characters to this drawing, the numeral 1 designates the bottom of the case, 2 the band section or wall, and 3 the cover. The bottom section is preferably of concave form and is provided with an upturned marginal flange 1^a which is designed to be spun over or engaged with a marginal flange or bead 2^a formed on the lower edge of the band section for the purpose of holding said parts together.

The powder receptacle comprises a pair of oppositely dished members 4 and 5 which are secured together to form therebetween a powder-holding compartment. The upper of these members is provided with a filling and discharge opening 4^a which is designed to be covered and uncovered by a movable cover member 6. The members 4 and 5 are preferably connected by a central rivet 7 and the cover is preferably rotatably mounted and held in position by the same rivet.

The said cover member is provided with a filling opening 6^a designed, in one position of the cover, to aline with the filling opening 4^a, and another portion is provided with a plurality of perforations indicated at 6^b designed to permit the proper dusting out or sprinkling of the powder.

A boss or projection 6^c facilitates the rotation of the cover to bring the proper portions in alinement with the opening 4^a, and of course an intact portion of the cover may be positioned over the filling opening 4^a to effect the closure thereof.

One of the members 4 and 5, and preferably the lower, 5, has its margin projected as indicated at 5^a and such marginal projection is designed to be placed between the bead or flange of the band section and the flange of the bottom of the box or case and be held therebetween when these parts are joined in the assembling of the parts of the case.

The band section is preferably provided with an overturned portion or flange 2^b which is provided with cut-away portions b, designed to be engaged by lugs 3^b on the cover 3 for holding the latter in position. The cover may carry a mirror as indicated at 8, and the case may have an enamel or other ornamental covering as desired.

Having thus described my invention, what I claim is:

An article of the class described comprising a box and a container for powder held in the bottom thereof and comprising two oppositely dished members, the upper dished member having an inturned peripheral flange, a filling opening in said member, a cover member superimposed upon said upper member, and a rivet connecting the central portion of said three members.

In testimony whereof I affix my signature.

GABRIEL FELSENTHAL.
